(57) **CLAIM**

The ornamental design for a bottle cap, as shown and described.

DESCRIPTION

FIG. 1 illustrates a bottom perspective view of bottle cap showing our new design.

FIG. 2 illustrates a top perspective view thereof.

FIG. 3 illustrates a bottom plan view thereof.

FIG. 4 illustrates a top plan view thereof; and,

FIG. 5 illustrates a sectional view, taken at line 5—5 in FIG. 4, to clarify the configuration of the exterior surface of bottle cap.

Portions of the bottle cap not shown in the drawing are disclaimed as forming no part of the claimed design.

The purpose of the broken lines in the drawings is as boundaries that form no part of the design.
